TRANSPORTATION CONTAINER

John P. McWilliams and Frank Ditchfield, Cleveland, Ohio, assignors to The Youngstown Steel Door Company, Cleveland, Ohio, a corporation of Ohio

Application January 9, 1932, Serial No. 585,708

20 Claims. (Cl. 189—46)

This invention relates to improvements in transportation containers, and more particularly that type of transportation container known as railway containers.

5 In the transportation of merchandise and other freight in so-called less than carload lots, by truck, railway and/or boat, the merchandise is placed in closed metal containers having pivoted doors on opposite sides thereof, which doors are then locked and sealed and transported from the source of origin to the consignee. Such containers are most frequently assembled on flat cars in groups and are subject to all kinds of weather conditions so that adequate provision must be 10 made for weather-sealing the several joints around the doors in order to prevent damage or injury to the contents while being transported.

Heretofore, two general methods have been employed to seal the door joints. One of such general methods utilizes rubber sealing strips or gaskets in or along the several door joints and the other general method utilizes spring pressed wooden strips beneath layers of canvas, felt and/or other fabric.

25 Experience has demonstrated that both of the above mentioned types of door sealing arrangements for containers are open to numerous serious objections. In the first place, both of said types of sealing means are relatively expensive in 30 first cost of application, both on account of the extra amount of material and parts required and also because of the additional labor required to apply the same. Furthermore, the rubber gaskets or seals soon deteriorate, thus necessitating re- 35 placement with its attendant expense. In the case of spring pressed packings, the wood backing strips soon dry out and become warped and the wear on the fabric is quite rapid. The spring pressed packings are also open to the objection 40 that considerable power is required in closing and opening the doors because of the resistance that must be overcome in compressing the packing.

Still another objection inherent in the foregoing described types of sealing arrangements in 45 the case of transportation of certain commodities, is that the sealed joints, when effective, are air tight so that air circulation to the interior of the container is prevented and hence "sweating" 50 is induced.

One object of this invention is to provide a transportation container economical to manufacture and maintain and wherein the joints around the doors are effectively and efficiently sealed against the weather without the use of

rubber gaskets, spring pressed packings or like attachments subject to deterioration.

Another object of the invention is to provide a transportation container having pivoted doors wherein the weather sealing of all the vertical door joints is obtained by means of freely interlocking parts, integral or fixed with respect to the several door framing elements and doors proper.

Another object of the invention is to provide a transportation container of the type indicated, 65 wherein the joint along the tops of the doors is effectively weather sealed by means of an automatically functioning sealing hood or flap.

A further object of the invention is to provide a transportation container wherein the foregoing 70 objects of invention may be attained in connection with doors of either the single or so-called double or folding leaf type.

Still another object of the invention is to provide, in a transportation container, simple, efficient and relatively inexpensive means for locking and sealing the doors in closed position, which means require manipulation of only a single member with a minimum number of movements to effect closure, locking and release of all 80 the doors and applicable to either doors of the single or so-called double or leaf type.

Another object of the invention is to provide a transportation container with joints around the doors such that, while completely effective to seal 85 the same against admission of rain, snow, sleet or the like, it at the same time allows of air passing through the joints in order to prevent sweating.

Other objects of the invention will more clearly 90 appear from the description and claims herein-after following.

In the drawings forming a part of this specification, Figure 1 is an end elevational view of a transportation container of the railway type, 95 showing the improvements in connection therewith, parts being broken away to better accommodate the view on the sheet and a portion of the pivoted hood or lintel being broken away to illustrate certain of the parts. Figure 2 is an enlarged horizontal, sectional view, corresponding substantially to the line 2—2 of Figure 1. Figure 3 is an elevational view, upon an enlarged scale, illustrating more particularly the closure operator for the doors, parts being broken away to 105 accommodate the figure on the sheet and the top sealing hood or flap being omitted. Figure 4 is a vertical, sectional view corresponding substantially to the line 4—4 of Figure 3. Figure 5 is a horizontal, detailed, sectional view, correspond- 110

ing to the line 5—5 of Figure 3. Figure 6 is a vertical, sectional view, upon an enlarged scale, corresponding to the section line 6—6 of Figure 1. Figure 7 is an enlarged, vertical, sectional view 5 corresponding to the line 7—7 of Figure 1. Figure 8 is a detail view corresponding to Figure 2, showing a modified form of a weather sealing flange. Figures 9 to 15, inclusive, are views similar to Figures 1 to 7, respectively, illustrating another embodiment of the invention. Figure 10 corresponding to the section line 10—10 of Figure 9, Figure 12 to the section line 12—12 of Figure 11; Figure 13 to the section line 13—13 of Figure 11 and Figures 14 and 15 corresponding to the section lines 14—14 and 15—15, respectively, of Figure 9. In Figure 9, parts of the container surrounding the door structure have been omitted in order to permit illustration upon a somewhat larger scale.

20 Referring first to the construction illustrated in Figures 1 to 7, the container is shown as having an end wall 20 in which the door arrangement is provided, it being understood that a duplicate arrangement will ordinarily be used on the opposite end of the container. The corner posts of the container are indicated at 21—21, the roof at 22, crane hooks 23—23 at the upper corners thereof and crane loops 24—24, two or more on each side at the roof. As will be understood, the 25 side walls of the container may be suitably braced to provide the necessary rigidity as by vertical corrugations 25—25.

Each door opening is defined by a top plate 26, which functions as the side or end plate of the 30 container, the same being of generally Z-formation with an upstanding flange 27, to which the roof sheets are secured, and an inwardly offset depending flange 28 constituting the lintel of the door framing. The side posts of the door 35 opening framework are defined by members 29 of generally channel formation, having one leg thereof elongated, as illustrated best in Figure 2. The bottom of the door opening is defined by a sill 30 of channel formation, as shown in Figure 40 7, that portion of the sill corresponding to the width of the door being inwardly offset from the remaining end portions of the sill, indicated at 45 30°. Secured to the sill is a threshold angle 31 between which and the sill is interposed a floor sheet 32 and on top of which lie the floor boards, indicated at 33. Secured to each of the posts 29, in the construction shown, is a channel 34 facing inwardly toward the door opening and 50 constituting what may be termed the jamb of the door frame.

In the arrangement chosen for illustration, the door opening is closed by two doors A and B, each of which in turn is comprised of two leaves, those of the door A being referenced 35 and 36 and those of the door B as 37 and 38. The doors 55 are mounted on sets of double hinges 39—39, fastened to the post 29 so as to permit the outer leaf of each door to swing back upon its inner leaf and still swing clear of the post 29 and be folded back against the wall of the container, as will be understood. The two leaves of each door are pivotally connected as by the hinges 40—40.

Each door, as shown, may be said to comprise a main sheet metal portion or panel with reinforced edges, the edges being varied somewhat on the individual leaves in order to conform to the corresponding adjacent members with which the weather seal is to be effected. Considering first the door leaf 37, the same comprises a main sheet 60 metal panel 41 of suitable gauge, which is in- clined outwardly along each of its vertical edges, as indicated at 42—43, and thence has its marginal portions extended parallel to the main plane of the door, as indicated at 44—45. Between the inclined portion 42 and 43, the panel 65 may be suitably reinforced by integrally formed horizontal corrugations 46. Secured to the inner sides of the flat marginal portions 44 and 45 are preferably formed channel shaped reinforcements 47 and 48, respectively, the channels facing toward the edges of the door, as clearly shown in Figure 2. To the lefthand edge of the door 37, as viewed in Figure 2, is secured a combined bracing and bridging strip or plate 49 for the full 70 length of the door, the same being riveted to the main panel sheets, as indicated at 50, and to the inner flange of the channel member 47, as indicated at 51. Said plate is extended beyond the edge of the door so as to provide a weather sealing flange 52, which is inclined outwardly and away from the door and adapted, when the door is in closed position, to extend within the corresponding channel jamb 34 to a point relatively close to the outer flange of the latter, it being 75 obvious that said inclined flange 52 bridges the gap or joint between the door and the adjacent jamb. At its opposite vertical edge, said door leaf 37 is provided with another vertically extending strip or bridging plate 53 likewise riveted to the main panel sheet, as indicated at 54, and to the inner flange of the bracing member 48, as indicated at 55. Preferably, the main panel sheet 80 will be offset, as indicated at 56—56, a distance corresponding to the thickness of the bridging plates 49 and 53 so as to obtain a substantially flush surface.

Referring now more particularly to Figures 6 and 7, the main panel 41 of the door 37 is inclined outwardly and away from the center of the panel at the top and bottom edges, as indicated at 56 and 57, respectively, the sheet then being continued to provide vertically extending flat marginal portions 58 and 59, respectively, at the top and bottom and to the inner sides of which are secured angles 60 and 61, respectively. The angles 60 and 61 will be extended to the vertical margins of the door over the top and bottom ends, respectively, of the side edge constructions. As will be understood, the door leaf 35 will be 90 made similar to the door leaf 37 and detailed description thereof is not deemed necessary.

The door leaf 38 has its lefthand edge, as viewed in Figure 2, constructed similar to that of the lefthand edge of the door leaf 37 and the same will be true of the righthand edge of the door leaf 36, as viewed in Figure 1. The righthand edge of the door leaf 38, since it is formed to provide a housing for the operating shaft, is of special formation, as shown in Figure 2. Instead of employing the channel edge member such as 100 47 or 48, the bridging or bracing plate 62, which is secured to the main panel at 63, is extended parallel to the main panel for a distance, is then extended outwardly at right angles, as indicated at 63, thence parallel with the outer marginal 105 flange, as indicated at 64, and beyond the marginal flange, and thence is bent inwardly at right angles, as indicated at 65, and terminates in a narrow inner edge flange 66. The main panel sheet and section 64 of the edge reinforcement 110 are secured by rivets 67.

The free edge of the remaining door leaf 36 is formed similar to the righthand vertical edge of the leaf 37, except that the bridging strip or plate 68 is extended beyond the door edge, as indicated 115

at 69, and is thence bent outwardly at right angles, as indicated at 70, so as to provide a flange which enters the channel or trough-like free edge of the door B. As will be understood, the top and bottom edges of the door leaves 36 and 38 are formed similar to the top edges of the other leaves 35 and 37.

With the construction shown and so far described, it will be seen that at each vertical joint 10 between the doors and jambs, between the leaves of each door, and between the meeting edges of the two doors, there is provided what may be termed a channel or trough-like construction on one member and an extended flange on the corresponding adjacent member, which is adapted 15 to enter the channel or trough-like formation when the doors are in fully closed position. It will further be evident that any rain, snow or sleet which may be driven through the cracks 20 or joints, will strike against a flange or section and thereby be deflected more or less outwardly and its momentum destroyed so that it will not pass the seals provided by the cooperating edge structures. At the same time, while the joints 25 are weather sealed as against the admission of rain or other foreign matter, nevertheless air may circulate to a limited extent between the interior and exterior of the container, thus preventing sweating.

Referring more particularly to Figure 7, it will also be noted that an effective seal has been provided at the bottom edges of the doors. Secured to the sill 30 is a horizontally disposed angle 71 having its upper flange arranged horizontally and 30 extending outwardly, as indicated at 72, which, when the doors are in closed position, is slightly spaced below the horizontal flanges of the bottom angles 61 of the doors, the latter in turn being disposed below the floor level. With this arrangement, any foreign matter driven inwardly 35 below the edges of the doors, will first be deflected by the angle 71—72 and even though some of the foreign matter may pass the joint between the flange 72 and the depending flanges of the door angles, its momentum will be sufficiently destroyed so that it cannot pass upwardly between the bottom door angles 61 and the threshold angle 31.

To provide the weather seal for the top edges 50 of the doors, the following arrangement is employed. Secured to the lintel for the full length thereof is a plate 73 (see Figure 6) which extends downwardly below the web section of the side plate and is first outwardly offset, as indicated at 55 74, and thence bent inwardly as indicated at 75. Pivotally mounted on the door posts at each of its ends, as by brackets 76 having pintles 77, is a hood or deflector plate 78, which extends upwardly behind the plate 73 where it has an outward turned flange 79 and which is extended down below the top edges of the doors and terminates in a downwardly and outwardly inclined flange 80. Said hood plate 78 normally hangs in the position shown in Figure 6 under the influence of 60 gravity, but is adapted to be swung outwardly about its pivot 77 when any one of the doors is opened. As clear from Figure 6, any rain or other foreign matter which may be driven inwardly below the flange 75 may pass the joint between 65 it and the hood plate 78, but its momentum will be sufficiently destroyed in the pocket above the flange 75 so that it will not pass over the flange 79. Similarly any foreign matter driven horizontally against the door below the shedding 70 flange 80 will strike the door panels and be de-

flected outwardly and the momentum sufficiently destroyed so that it cannot pass up through the relatively wide joint between the hood plate 78 and top marginal portions of the doors.

To lock or latch the doors in closed position, the following arrangement is employed. Referring to Figures 2 and 6, the door leaf 38 is provided at the top thereof at its inner or hinged edge, with a bracket 81 of generally angular formation, as viewed in Figure 6, the depending flange thereof being riveted to the top edge of the door construction, as indicated at 82. The horizontal flange of said bracket is extended inwardly beyond the inner face of the door and at its inner end is formed with a lug or hook 83, which is adapted to enter through an opening 84 provided therefor in the depending flange of the top plate or lintel 26. When the door leaf 38 is in fully closed position, as shown in Figure 2, said hook or lug 83 engages behind the lintel and hence prevents the door from opening outwardly at the pivot joint between the leaves 37 and 38. As will be understood, a corresponding arrangement is employed at the upper end of the door leaf 36. At the bottom and also adjacent the pivotal connection thereof, the leaf 38 is provided with a corresponding bracket 85 of angular form, the vertical flange of which is riveted to the lower edge of the door, as indicated at 86, and the other horizontal flange of which is formed with a hook or lug 87, which is adapted to enter through aligned slots 88 formed in the sill 30 and the depending flange of the angle 71—72, as shown in Figure 7. In this manner, the bottom of the door will be latched against the sill and prevent opening movement thereof unless and until the leaf 38 is first swung about its hinges 40. The outer leaf 36 is similarly equipped with a lower latching hook, as will be understood.

At the free vertical edge of the leaf 38, which is closed last and overlies the leaf 36, there is rotatably journaled in the inwardly facing channel formation, an operating shaft 88 of preferably hollow, tubular formation for the greater part of its length and having secured thereto at 105 its upper and lower ends crank arm castings 89 and 90 respectively. The shaft is journaled in suitable bearing openings provided in the top angle 60 and bottom angle 61. Each of said castings 89 is formed with a crank-like hook shaped arm 91—91, which are adapted to enter through corresponding slots 92 and 93 provided in the lintel and sill respectively so that, when the doors are fully closed and the shaft rotated to the position best indicated in Figure 5, said hooks will engage behind the lintel and sill and thus hold the doors closed. For operating the shaft at a convenient level, the lower casting 90 is formed with an extended arm 94, which is also adapted to act as a hasp, the same being slotted as indicated at 110 95 to seat over a staple 96, through which may be inserted a retaining pin or the like in the holes 97 provided therefor. Preferably, all of the upper hook shaped lugs or arms for latching the doors will be protected from the lading by suitable housing castings 98 riveted to the inner face of the depending flange of the lintel or side plate. In this connection, it will be observed that the operating shaft is housed from the weather due to its location within the channel formation at 115 the free edge of the door B and is likewise effectively protected against injury.

In the modification shown in Figure 8, the weather sealing flanges carried by the lefthand edges of the leaves 37 and 38 (and similarly the 120

righthand edges of the leaves 35 and 36, as will be understood) instead of being plain or flat, have an arcuate corrugation 252 formed therein with the concave face thereof directed generally toward the outer crack or joint between the doors. With this construction, when the rain or other foreign matter is driven inwardly through the crack, such portions thereof as strike the flange 252 will be deflected and given a more or less whirling motion so as to throw the same off of the free edge 352 of the flange toward the crack and hence reduce still farther the possibility of any of the foreign matter passing over the edge of the flange to a position behind it.

15 Referring next to the construction illustrated in Figures 9 to 15, the general arrangement is the same as that for the construction already described. As before, two doors A' and B' are employed, each consisting of two pivotally connected leaves, as indicated at 135, 136, 137 and 138, respectively, and hinged in the same manner as previously described. To the side door posts 129 are riveted vertically extending formed sheet metal jambs 134, each of which differs, however, from the jambs 34 by having an additional inwardly extended inner flange 234, thus still preserving the general channel or trough-like formation but with a somewhat narrowed opening or mouth, as will be clear from Figure 10.

20 The door leaf 137 consists of a main sheet metal panel 141, the main plane of which is disposed outwardly instead of inwardly, as in the first described construction. Along its vertical edges, the panel 141 is formed with inwardly extending inclined sections 142-143, terminating in inner flat marginal sections 144 and 145, respectively. To these edge portions of the sheet metal panels are secured edge bracing plates 148 and 149, each of which is of generally Z-section, the outer 25 flanges of which are riveted to inwardly offset portions of the panel, as indicated at 248 and 249 and the inner flanges of which are secured to the flat margins of the panel by rivets, as indicated at 151 and 155, respectively. The lefthand edge 30 brace 149 is continued and has integrally formed therewith, the weather sealing flange 152 so arranged that it is adapted to enter through the mouth of the jamb strip 134 when the leaf 137 is swung about its pivotal axis. In this construction, as shown in Figure 10, any rain or other foreign matter driven between the flange 234 and the member 149 must first be deflected at right angles and then will be again deflected by the inclined flange 152 and its momentum destroyed 35 so that danger of the same passing around the free edge of the flange 152 is eliminated. As will be understood, the door leaf 135 will have its outer hinged edge similarly formed to cooperate with a similar jamb 134. At its free edge, the leaf 40 137 has an additional weather sealing member 448 applied thereto, which is of channel or U-section facing inwardly and riveted to the member 148 as by the rivets 348, thus forming a channel or trough formation with a somewhat narrowed mouth similar to that of the jamb 134.

45 The top of the leaf 137 is formed by extending the sheet metal panel 141 inwardly and upwardly, as indicated at 156, which terminates in a vertical marginal flange 158, to which is riveted, on the outer side thereof, an angle 160. The lower edge of the door, as shown in Figure 15, is similarly formed by extending the panel inwardly and downwardly, as indicated at 157 and terminating 50 the same in a flat marginal flange 159 to the outer

side of which is secured a bottom reinforcing angle 161.

The leaf 138 is formed at the top and bottom the same as the leaf 137 and the same is also true as regards the lefthand vertical edge of the leaf 138, which is similar to the lefthand edge of the leaf 137. Along its free or righthand vertical edge, as viewed in Figure 10, the leaf 138 has secured thereto a specially formed reinforcing section 163 providing an outwardly facing channel 263 and an inwardly facing channel 363. The channel section 263 provides a recess for accommodating the vertically extending operating shaft 188 corresponding to the shaft 88. The free edge of the leaf 138 has a reinforcing member 169 secured thereto, so formed as to present an outwardly facing channel 269, the flange 369 of which enters the inwardly facing channel 363 of the adjacent door and within which channel 269 is received the inwardly extending flange 463 thereof. With this construction, the door B', when closed, securely retains the door A' and a double joint weather seal is provided between the interfitting channel formations at the free edges thereof, shown in Figure 10.

55 At the top and bottom thereof, each leaf 138 and 136, adjacent its hinge connection, is provided with latching brackets 181 and 185 corresponding to the similar brackets 81 and 85, respectively, and adapted to engage the lintel and sill, respectively. The operating shaft 188 is similar to that previously described except that the upper casting 189 is provided with an additional lug or kicker 289 (see Figure 13), which is adapted to engage and push out the pivoted hood 178 in advance of the actual opening movement of the door. The pivoted hood 178 is mounted and functions in the same manner as the hood 78 except that the same is formed with a right angular flange 180 at its bottom edge instead of an inclined flange 80.

60 From the preceding description, it will be observed that effective weather seals against the admission of any foreign matter are provided between all vertical joints and also along the top and bottom edges of the doors, said weather sealing formations being further characterized by the fact that they will permit circulation of air to the interior of the container. All the formations, as obvious, are of metal, thus doing away with all 65 rubber, fabric and springs for such purposes as heretofore employed. It will also be noted that all edges of the doors are thoroughly reinforced and braced against collapse or twisting and that, with respect to all vertical edges of the doors, a 70 tubular formation is present whereby great strength per unit of weight of material is obtained.

75 The invention has been shown and described in what is now considered its preferred form but 75 obviously various changes and modifications may be made without departing from the spirit of the invention, and all such changes are contemplated as come within the scope of the claims appended hereto.

80 What is claimed is:

85 1. A transportation container having a door opening; a pair of oppositely swinging doors adapted to close said opening; and means providing a weather seal joint at the meeting edges of the two doors, said means including a channel formation on the edge of one door opening inwardly and a plate-like section on the edge of the other door, said section extending beyond the edge of the channel flange and having an 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 - out-turned flange at its extremity extending within the channel, said formation and section overlapping and interlocking when the doors are in closed position.
- 5 2. A transportation container having a door opening; a door for said opening pivotally connected to the door post, the door comprising two leaves pivotally connected; and means providing a weather seal joint at the adjacent edges of the two door leaves, said means including a trough-like section along the edge of one of the leaves and a flange projecting from the opposed edge of the other leaf, said flange being disposed within the trough section when the door is in closed position. 80
- 10 3. A transportation container having a door opening; two doors pivotally connected to the container to swing about axes paralleling the door posts, each door comprising two pivotally connected leaves; and means providing a weather seal at all of the vertical joints between the doors and posts, each of said means including a vertically extending trough-like section on one element and a flange on the corresponding post element positioned within the trough section 85 when the doors are in closed position.
- 15 4. As an article of manufacture, a metal door adapted for pivotal mounting about a vertical axis on a container, said door having the main body portion thereof comprised of sheet metal and provided along its vertical side edges with weather sealing formations, the formation along one edge being of trough-like form and the formation along the opposite vertical edge including a flange 90 inclined outwardly and away from the center of the door.
- 20 5. A transportation container having a door opening; a door for said opening pivoted to swing about a vertical axis; and means movably mounted on the outside of the container extending lengthwise of the lintel of the door opening, said means overlapping the joint between the top of the door and the lintel when the door is in closed position and forming a weather seal for said 95 joint, said means being automatically displaced by and when the door is opened and assuming normal operative position under the influence of gravity when the door is closed.
- 25 6. A transportation container having a side door opening; a pair of pivoted oppositely mounted doors to close said opening; and means movably mounted on the outside of the container extending the entire length of the lintel of the door opening and overlapping the joint between 100 the top edges of both doors and the lintel when the doors are in closed position to form a weather seal therefor, said means being automatically displaced by and when either door is opened and assuming normal operative position under the influence of gravity when and as both doors are closed.
- 30 7. A transportation container having a door opening; a pair of pivotally mounted doors adapted to swing about vertical axes adjacent the respective door posts; weather sealing means between the door posts and the edges of the doors adjacent thereto and at the meeting edges of the doors; a hood plate on the outer side of the container extending lengthwise of the lintel of the door and pivotally mounted to swing about a horizontal axis, said plate normally depending and overlapping the joints between the tops of the doors and the lintel when the doors are in closed position and adapted to be automatically 105 displaced by and when either door is opened.
- 35 8. A transportation container having a door opening; a pair of doors therefor, said doors being pivotally mounted to swing about vertical axes adjacent the door posts and each door comprising two leaves pivotally connected; means providing a weather seal for all of the vertical joints between the posts and doors and adjacent edges of the doors and door leaves, each of said means including a trough-like section on one element and a flange on the opposed element 110 adapted to enter the trough section when the doors are in closed position; a hood plate on the outer side of the container pivotally mounted to swing about a horizontal axis parallel and adjacent to the lintel, said plate normally depending and overlapping the joints between the top edges of the doors and the lintel and adapted to be swung outwardly by and when either door is opened. 115
- 40 9. A transportation container having a door opening defined by a bottom sill, a lintel and side posts; a door pivoted to swing about a vertical axis adjacent one of the side posts; and manually operable means rotatably mounted about a vertical axis adjacent the free edge of the door, said means having arms movable in a horizontal plane into and out of cooperable latching engagement with said sill and lintel. 120
- 45 10. As an article of manufacture, an all metal door having a weather sealing edge and adapted for pivotal mounting, said door having the main body portion thereof comprised of sheet metal with all of its edges inclined inwardly and away from the center of the door and with said inclined portions terminating in flat marginal portions 125 parallel to the main plane of the sheet; reinforcing members secured along the top and bottom edges of the door to and on the outer sides of the flat marginal portions thereof; reinforcing means secured along one vertical edge of the sheet metal main portion; and a reinforcing weather sealing element secured along the other vertical edge of the sheet metal portion, said element being of substantially Z cross section with a portion of one of its flanges inclined outwardly and away from 130 the center of the door.
- 50 11. As an article of manufacture, an all metal weather sealing door adapted for pivotal mounting, said door comprising a main sheet metal portion, all edges of which are inclined outwardly 135 from the main plane of the sheet and away from the center thereof and terminate in flat marginal portions outwardly offset from the main plane of the sheet; reinforcing members secured to the inner faces of the top and bottom marginal portions; reinforcing means extending along and secured to one vertical edge of the main sheet; a reinforcing element of channel section secured to the inner face of the other vertical flat marginal portion with the channel facing outwardly; and a combined weather-sealing and bracing strip secured to the inner flange of the channel and to the main part of the sheet, said strip having its outer edge extended beyond the channel and inclined outwardly away from the center of the door. 140
- 55 12. A transportation container having a door opening defined in part by a sill along the bottom thereof and flooring supported on the sill; an all metal door pivotally mounted about a vertical axis to close said opening, the lower edge of the door extending down below the level of said flooring; and means providing a weather seal along the bottom edge of the door, said means including: an angle secured to the sill below the level of 145
- 60 75 150

- the surface of the flooring and having its upper flange extending horizontally outwardly, and an angle secured to the inner face of the bottom edge of the door with an upper flange extending horizontally inwardly in slightly spaced relation above said first named flange when the door is in closed position, said upper flange of the door angle being located in a plane below the surface of the flooring. 80
- 10 13. In a railway type container having a door opening, the combination with a fabricated metal door member and an adjacent member, said two members being pivotally connected to swing relatively about a vertical axis; of means providing a weather seal joint between the adjacent vertical edges of said two members, said means comprising: a sealing element on one member having inner and outer, laterally spaced sections extending toward the other member, inner and outer sections on said other member located in planes corresponding to said laterally spaced sections, the last named inner section having a flange extending outwardly therefrom into the space between said first named laterally spaced sections. 85
- 15 14. In a railway type container having a door opening, the combination with a fabricated metal door member and an adjacent member, said two members being pivotally connected to swing relatively about a vertical axis; of means providing a weather seal joint between the adjacent vertical edges of said two members, said means comprising: channel shaped formations on both members, the open mouths of the channels facing each other, and one of said formations having also a flange extending outwardly from the inner flange of its channel into the other channel formation. 90
- 20 15. A transportation container having a door opening in one wall thereof; a lintel across the top of said opening and inwardly offset from the general plane of the wall; a door for said opening and pivotally mounted to swing about a vertical axis, said door, when closed, occupying the space between the outer plane of the side wall and lintel; and a hood plate pivotally mounted to swing about a horizontal axis parallel and adjacent to the lintel, said plate normally extending downwardly beyond the upper edge of the door in engagement with the outer face of the door whereby, as the door is opened, said hood plate is automatically swung outwardly about its pivot and, when the door moves to closed position, automatically drops downwardly to operative position. 95
- 25 16. A transportation container having a door opening in one wall thereof; a combined side plate and lintel extending across the top of said door opening, the lintel section thereof being inwardly offset within the door opening; a hood plate pivotally mounted adjacent said side plate and lintel and normally hanging downwardly under the influence of gravity; and a pivotally mounted door for said opening, the upper portion of the door being disposed between the hood plate and the lintel when the door is in closed position. 100
- 30 17. A transportation container having a door opening defined by top and bottom framing members and side posts; a pivotally mounted door for said opening, said door comprising two leaves pivotally connected; means rigid with the outer door leaf at one end thereof adjacent its pivotal connection with the inner leaf; and cooperable shouldered means on the corresponding adjacent framing member with which said first named means is adapted to latch when and as said outer leaf is moved to closed position. 105
- 35 18. A transportation container in accordance with claim 17 wherein said means rigid with the outer door leaf is in the form of a hook and said cooperable shoulder means on the framing member is provided by a slot in the latter through which the hook enters. 110
- 40 19. A transportation container in accordance with claim 9 wherein said sill and lintel are slotted and said arms are of hook shape and adapted to enter through the slots and engage the inner faces of the sill and lintel adjacent the slot. 115
- 45 20. In a railway car container having a door opening, the combination with a fabricated metal door member and an adjacent member, said two members being pivotally connected to swing relatively about a vertical axis; of means providing a weather seal joint between the adjacent vertical edges of said members when the door member is in closed position, said means comprising: a sealing element on one member having an inner flange and a laterally spaced outer flange both extending toward the other member, said outer flange having a terminal flat section extended inwardly at right angles to the flange of which it forms a part, said other member having an inwardly extending section adjacent and parallel to said terminal flat section; and an outwardly inclined terminal flange adapted to enter the space defined by said first named flanges and flat marginal section. 120
- 50 55 16. A transportation container having a door opening in one wall thereof; a combined side plate and lintel extending across the top of said door opening, the lintel section thereof being inwardly offset within the door opening; a hood plate pivotally mounted adjacent said side plate and lintel and normally hanging downwardly under the influence of gravity; and a pivotally mounted door for said opening, the upper portion of the door being disposed between the hood plate and the lintel when the door is in closed position. 125
